UNITED STATES PATENT OFFICE

CHARLES LAWRENCE STOKES, OF LOS ANGELES, CALIFORNIA

LIQUID-FEED SYSTEM

Application filed December 5, 1923. Serial No. 678,648.

My invention relates to improvements in vacuum tanks, which are commonly used for supplying liquid fuel from a low level to an internal combustion engine at a higher level, the same being operated by the vacuum of the engine.

The principal object of my invention is to provide a vacuum tank wherein a single chamber functions as efficiently as the double chamber vacuum tanks now well known in the art, and which may be very cheaply constructed.

Referring to the drawings, in which the same numbers indicate like parts:—

Fig. 1 is a sectional view of my apparatus. Fig. 2 is a view and part section along the lines A—A of Fig. 1.

Fig. 3 is an alternative to be used in place of part of Fig. 1.

The vacuum tank comprises a chamber or receptacle 1, which is closed on its upper end by a cover 2, 1 and 2 being held together by a set of screws 3 usually having an interposed gasket. A boss 4 is provided to be connected by piping to a low level fuel supply tank (not shown). A boss 5 is provided to be connected by piping to the manifold of an interior combustion engine, for applying the engine vacuum to the interior of 1 through a restricted orifice 29. The lower part of 1 contains a central boss 6, having passages 7 therein communicating with the interior of 1. An annular ring 8 is threaded on 6 to form a chamber containing a light check valve 12 with passages 13 therethrough. The lower part of 8 is closed by a plug 9 having a threaded passage 10 adapted to be connected to the carburetor of the engine and feed liquid fuel thereto by gravity.

An annular float 14 is placed in 1 and on the upper side of 14 are diametrically opposite pins 15 and 15^a to each of which is fastened Bourdon tubes 16 and 16^a respectively.

Centrally of 14, and also of 1, is a hollow receptacle 17 forming a guide for float 14 of relatively large diameter, which terminates

at its lower end in a hollow stem 18 adapted to slide through the center of 6 and the interior of 17 is open to the interior of 8 through 18. The upper end of 17 is surrounded by an annular shoulder 20, being centrally closed by a plug 19, and 20 is designed to be a predetermined distance from the inner face of 2 when a valve 21 connected to 17 is seated in a central boss 23 placed on the upper side of 2. 21 contains a passage 22 connecting the interior of 17 with atmosphere.

Bourdon tubes 16 and 16^a each filled with a gas at atmospheric pressure, terminate in arms 24 and 24^a respectively, which are adapted to substantially parallel the periphery of 17 at a predetermined distance therefrom.

The operation is as follows:—

The application of engine vacuum through 5 and 29 to the interior of 1 is controlled by the side of port 29 and when vacuum is applied therethrough, fuel will flow in through 4 and at the same time the vacuum will cause an expansion of tubes 16 and 16^a, whereby 24 and 24^a will firmly grasp the exterior of 17, it being noted that normally valve 21 is seated by the weight of 17 thus excluding atmosphere from the interior of 1. The action of the inflowing liquid through 4 causes float 14 to become increasingly submerged, because check valve 12 will have been seated by the vacuum on the lower face of 6 thereby closing passages 7, and inasmuch as 14 is now firmly attached to 17 by means of 24, when 14 has been submerged a predetermined distance, the buoyancy of 14 will have caused valve 21 to lift suddenly thus admitting atmosphere to the interior of 1 and breaking the suction being applied therein through 29.

The suction thus being broken by the admission of air through 21, a contraction of 16 and 16^a occurs, thus releasing 24 and 24^a from 17, and also causes valve 12 to drop onto 11, and therefore liquid fuel is discharged through 7, 13 and 10 to the carburetor. At the same time liquid fuel rises to static level on the interior

of 17 through 18, and 14 will also rise a predetermined distance in 1 due to its increased buoyancy by releasing the weight of 17 therefrom.

5 Guide 17 now falls closing 21 and 12 and the cycle is repeated, except that 14 reaches increasing levels until it strikes against the shoulder 20 when 1 becomes full. It must be noted that, in order to supply the engine continuously with fuel during both the pumping and dumping periods, during each suction period when liquid fuel is being drawn in through 4, the liquid within 17 will be flowing through 18 to feed the carburetor, because 10 the interior of 17 is open to atmosphere through 22, and 17 is so designed to take care of this effect.

Consequently, when 1 becomes full, 17 is also filled and 1 then becomes a reservoir for 20 liquid fuel to be supplied to the engine at such critical periods of engine operation as when the vacuum being applied to 29 is insufficient to raise fuel to 1 from a low level, the fuel being released from 1 at this critical 25 period by the exhaustion of the fuel within 17 and thereafter the admission of air through 22, 17, and 18 to the interior of 8, when the same passes up around the stem 18 and is of sufficient volume to break the 30 very light vacuum then being applied through 29 so that the liquid in 1 will feed to the carburetor.

The alternative shown in Fig. 3 functions in a similar manner to permit the fuel in 1 35 to be discharged therefrom under conditions of low vacuum when liquid fuel cannot be lifted thereto.

A fitting 25 is threaded into 6 and contains a central boss 27 through which 18 slides and 40 is closed by a check valve 26.

The check valve 26 opens and closes by the alternation of suction and atmospheric pressure in the well known manner and a small hole 28 is provided in 25, whereby when the 45 liquid in 17 is exhausted, atmosphere may be admitted through 22, 17, 18, and 28, to the interior of 1 for breaking the low vacuum being applied through 29, but in both illustrations the amount of air admitted to 1 50 through 28 in Fig. 3, or around 18 in Fig. 1, is insufficient to affect the pumping efficiency of 1 under high vacuum. It may be noted that the surfaces of 16, 16^a and 17 may be roughened, or corrugated to ensure a good grip.

55 I claim:

1. A vacuum tank including a main chamber having a port for applying suction continuously to said chamber, a port for supplying liquid fuel, a port for supplying air, a port for discharging liquid fuel, a float in the chamber, and means including mechanism actuated by the pressure in the chamber for creating alternations of vacuum and atmospheric pressure in the chamber.

60 2. A vacuum tank including a main chamber

70 having a port for applying suction continuously to said chamber, a port for supplying liquid fuel, a port for supplying air, a port for discharging liquid fuel, a float in the chamber, and means actuated by pressure in said main chamber and associated with the float for creating alternations of vacuum and atmospheric pressure in the chamber.

75 3. A vacuum tank including a main chamber having a port for applying suction to said chamber, a port for supplying liquid fuel, a port for supplying air, a port for discharging liquid fuel, a float in the chamber, a movable receptacle in the chamber communicating at its lower end with the liquid discharge 80 port, a valve associated with the receptacle for opening and closing said air port upon movement of the receptacle, and means actuated by the pressure within said chamber and associated with the float for causing the 85 float to move said receptacle and open said air port when suction is applied to said chamber.

90 4. A vacuum tank including a main chamber with suction, air and fuel ports, and a float 95 in the chamber having a portion responsive to the pressure within the main chamber for controlling the supply of air and liquid fuel through said ports, said suction port remaining constantly open.

100 5. A vacuum tank for the fuel feeding system of an internal combustion engine, including a main chamber having a port through which the suction of the engine is applied, a port for supplying liquid fuel, a port for supplying air, a port for discharging liquid fuel, a float in the chamber, a hollow guide for the float, and means of discharging liquid fuel from the guide during the application 105 of engine suction to the chamber.

110 6. In a fuel feeding system for internal combustion engines, a receptacle for liquid fuel having an air inlet, a permanently open suction port, a valve for said inlet, and means comprising a pressure controlled device for 115 operating said valve.

115 7. In a fuel feeding system for internal combustion engines, a vacuum tank comprising a receptacle, a chamber associated with said receptacle, said receptacle being provided with an air intake port, a valve for said port and a guide for said valve, said guide being provided with an opening extending longitudinally thereof for supplying air at atmospheric pressure to said chamber.

120 8. In a fuel feeding system for internal combustion engines, a receptacle for liquid fuel, said receptacle being provided with an air inlet port, a permanently open air exhaust port, and a fuel inlet port, valves for said fuel and air inlet ports, and means including mechanism controlled by the variation of pressure within said receptacle for 125 opening said air inlet valve when the liquid 130

within said receptacle rises above a predetermined level.

9. In a fuel feeding system for internal combustion engines, a vacuum tank comprising a receptacle having an air inlet, a valve for said inlet, means for operating said valve, said means comprising a float and a pressure controlled device for gripping, with said float for operating said valve.

10. Signed at Wilmington, in the county of Los Angeles and State of California, this 6th day of November A. D. 1923.

CERTIFICATE OF CORRECTION.

Patent No. 1,736,100.

Granted November 19, 1929, to

CHARLES LAWRENCE STOKES.

It is hereby certified that error appears in the printed specification of the above numbered patent requiring correction as follows: Page 1, line 65, for the word "side" read "size"; page 3, line 8, claim 9, strike out the word "with" and the comma immediately preceding it; and that the said Letters Patent should be read with this correction therein that the same may conform to the record of the case in the Patent Office.

Signed and sealed this 31st day of December, A. D. 1929.
